UNITED STATES PATENT OFFICE.

FRANKLIN FYLES, OF NEW YORK, N. Y.

DESIGN FOR AN ENVELOPE.

SPECIFICATION forming part of Design No. 21,277, dated January 5, 1892.

Application filed October 21, 1891. Serial No. 409,417. Term of patent 7 years.

To all whom it may concern:

Be it known that I, FRANKLIN FYLES, a citizen of the United States, residing at 114 West Ninety-fourth street, New York city, 5 in the county and State of New York, have invented and produced a new and original Design for Printed Envelopes, of which the following is a specification, reference being had to the accompanying drawing.

10 The figure there shown is my design for a printed envelope.

The leading feature of my design consists of two outlined blank spaces, each one inch high and seven-eighths of an inch wide, these 15 two spaces being placed at the upper corners

of an envelope on its address side and connected with each other across the upper part of the envelope by an outlined blank space. The connecting-space is arched in shape and ornamented with scroll-work along its outer 20 edges. Scroll-work extends downward from the other two spaces.

What I claim is—

The design for an envelope, as herein shown and described.

FRANKLIN FYLES.
